UNITED STATES PATENT OFFICE.

HENRY J. CHILTON, OF CHICAGO, ILLINOIS.

BOTTLE-HANDLING MACHINE.

1,132,162.

Specification of Letters Patent. Patented Mar. 16, 1915.

Application filed January 3, 1910. Serial No. 536,012.

To all whom it may concern:

Be it known that I, HENRY J. CHILTON, a citizen of the United States, residing in the city of Chicago, county of Cook, and State of Illinois, have invented certain new and useful Improvements in Bottle-Handling Machines, of which the following is a specification.

This invention relates to improvements in bottle handling machines, and refers more particularly to improvements in construction of machines of that character, commonly known as rotary cappers.

Among the salient objects of the present invention are to provide a machine of the character referred to in which the bottles after being filled are shifted into alinement with capping devices and there automatically capped; to provide in a construction of this general character novel mechanism for automatically shifting the bottle holders successively into their various positions, said shifting mechanism being positively operated by simple cam mechanism; to provide equalizing means whereby the bottles are capped by the uniform and predetermined pressure regardless of any inequalities in the size of the bottles; to provide an improved form of hopper for automatically feeding the caps to the delivery chutes; to provide means for insuring a more accurate and reliable feed of the caps to the capping devices in which each capper is provided with an individual chute; to provide a machine in which the various operating mechanisms are accurately controlled by simple cam mechanisms and in which the various mechanisms are operated in properly timed relation; and in general to provide an improved form of construction of the character referred to.

The invention consists in the matters hereinafter described and more particularly pointed out in the appended claims.

In the drawings--Figure 1 is a front side elevation of my machine, parts being broken away, and other parts shown in section, in order to more clearly bring out details of construction; Fig. 2 is a horizontal vertical sectional view taken approximately on lines 2--2 of Fig. 1 and looking in the direction of the arrows; Fig. 3 is a diagrammatic view of the bottle holders and associated mechanism shown as laid out flat; Fig. 4 is a vertical sectional view, partly in side elevation of the mechanism for vertically recip-

rocating the bottles; Fig. 5 is a fragmentary horizontal sectional view taken on lines 5--5 of Fig. 4 and looking in the direction of the arrows; Fig. 6 is a detail sectional view 60 taken on lines 6--6 of Fig. 4 and looking in the direction of the arrows; Fig. 7 is a fragmentary vertical sectional view showing the means for actuating the rack bar which reciprocates the bottle holders; Fig. 8 is an 65 inverted fragmentary plan view of the gears which operate the rack bars and showing also an associated cam track; Fig. 9 is a fragmentary vertical sectional view of the hopper; Fig. 10 is a similar sectional view 70 taken on lines 10--10 of Fig. 9 and looking in the direction of the arrows; Fig. 11 is a similar view taken on lines 11--11 of Fig. 9 and looking in the direction of the arrows; Fig. 12 is a detail sectional view of the 75 lower portion of one of the chutes and associated capper. Fig. 13 is a sectional detail view of a portion of the delivery chute. Fig. 14 is a sectional detail view of a washer associated with one of the rack bar 80 plungers. Fig. 15 is a sectional detail view of a portion of the hopper mechanism.

Referring to the drawings, 1 designates as a whole a ring-like base casting provided with a cylindrical extension 2 and an annular raceway 3 which supports a skeleton-like, cylindrical casting 4. The latter is provided at its lower end with a closed air chamber 5 which is arranged to telescope over the cylindrical extension 2 and ride 90 upon the raceway 3. To the upper part of the rotating frame is secured a ring-like casting 6 which rests upon an annular shoulder 7 and is secured in position by means of suitable through bolts 8. This 95 casting is provided with a plurality of radially extending bosses 9 which are adapted to receive vertically extending posts 10. The latter also extend at the lower ends through similar bosses 11 carried by a 100 bracket 12 bolted or otherwise secured to the rotating main frame 4. To the lower end of the main frame 4 is likewise secured a circumferentially extending casting 13, the outer edge of which is provided with a 105 series of cylindrical socket members 14 which are arranged in alinement with the post 10 hereinafter more particularly described. Upon the ring-like casting 6 is mounted a skeleton upper frame 15 which 110 supports the filling mechanism as a whole. This frame 15 may be secured in position by

the through bolts 8 extending through an annular flange 16 upon the lower edge of the frame 15. Upon the upper edge of this frame 15 is mounted the filling tank 17 which is provided with the usual filling tubes 18 all in a well known manner. The tank is preferably provided with a removable cover 19 and regulating float 20. The tank is filled by a supply pipe 21 extending vertically through the center of the machine and communicating with the cross pipe 22 leading to any suitable source of supply.

Referring now particularly to the manner of raising and lowering the bottles, upon the upper end of each post is secured a cap 24 having a radial extension 24'. Upon each of these caps is mounted a bottle holder designated as a whole 23 which is preferably of two-part construction, comprising a slide 25 and a detachable rest 26. Each slide 25 is secured to the corresponding cap 24 by a dovetail connection 28 shown more clearly in Fig. 4. The rests 26 are provided with lugs 27' extending into suitable recesses 27 formed in the opposed faces of the slides whereby the rest may be readily removed. This permits of adapting the holders to bottles of various sizes. In the present instance, the caps 24 telescope over the upper end of the posts and are secured in position by means of suitable set screws 27'. The manner of reciprocating the bottle holders into their various operative positions will be hereinafter described.

Describing now the manner of supporting the capping devices and hopper, to the base casting are secured a series of vertical standards 29 of which there are four. The lower ends of these standards are screw threaded into the base casting as shown at 29'. The upper end of each standard is provided with a screw threaded extension 29' upon which is adjustably mounted a sleeve 30 loosely seated in a boss 31 carried by a ring-like casting 32 which extends around the filling tank 17. In order to adjust the capping mechanism to bottles of various sizes, these sleeves and the associated ring-like casting 32 may be raised and lowered upon the standards 29. Accordingly, the sleeve is provided at its upper end with an integral nut 33 and at its lower end with a detachable nut 34, between which and the boss 31 is secured a spur gear 35. This gear is splined to the sleeve as shown at 36. Each of these gears 35, it being understood that there is one for each post, is adapted to mesh with a relatively large gear 37 which extends entirely around the machine. This gear is secured in position by means of a confining plate 38 secured to the ring-like casting 32 by means of bolts 39. The inner face of the ring-like casting is provided at its upper edge with a shoulder 40, between which and the confining plate 38 is secured

an extension 41 of a cylindrical casting 42. Upon the upper end of this casting is mounted the inner side wall 43 of a hopper 44, V-shaped in cross section which extends circumferentially of the machine as shown 70 most clearly in Fig. 1. The opposite side wall 45 of the hopper is bolted as shown at 46 to brackets 47 integral with the ring-like casting 32. It may here be noted that the converging side walls of the hopper are 75 slightly spaced away from each other at their lower ends as shown at 48 (Fig. 11). The inner side wall 43 is provided at its lower edge with slots 49' corresponding in number to the bottle holders. These slots are of 80 such size as to permit the head of a cap to pass therethrough into the adjacent delivery chutes 49.

Describing now the cappers and associated chutes, the inner cylindrical casting 42 85 is provided with a downwardly extending flange 51, to the lower end of which is secured a plurality of cappers 52, 52. Each of these cappers is provided with a delivery chute 49. Each of these chutes communicates at its lower end with the bottom of the corresponding capper as shown at 53 and at its upper end registers with the open space 48 at the bottom of the hopper. Each chute passes through a suitable aperture 54 95 in the cylindrical casting 42 and is fixed at its upper end to the latter by means of a clamp 55. The outer side wall of the hopper is, of course, stationary with the ring-like casting 32 while the inner side wall 43 100 is adapted to rotate with the main frame of the machine. To this end the frame 15 is provided with a plurality of lugs 56 which enter suitable recesses in the casting 51 of the cylindrical casting 42. In order that the latter may rotate more freely, a series of rollers 57 are interposed between the upper face of the extension 41 and the flange 40. These rollers are placed between the opposed upper surfaces of these castings instead of 105 between the lower bearing surfaces in order to eliminate the friction due to the upward pressure applied in capping. It is to be here noted that the capping devices and the hopper are supported by the outer standards 29 instead of by the rotating main frame in order to relieve the rotating main frame of 110 excessive strains due to the capping and also to permit the cappers being more readily adjusted for bottles of different sizes. It is 115 also to be noted that the cappers may be lowered by simply turning one of the nuts 33, through the action of the gear mechanism heretofore described.

The novel manner of feeding the caps to 120 the various capping devices forms an important feature of the invention. The rotating part of the hopper agitates the caps so that they are brought in proper position to pass through the various recesses 49' into 130

the chutes. The use of individual chutes for each capper permits of a slower and accordingly more accurate feed of the caps. It may also be noted that the chutes and cappers are thus entirely independent of each other. If for any reason any chute should stop up or get out of order, it would not disable the remainder of the cappers.

Describing now the manner of reciprocating the bottles into and out of engagement with the filling tubes, within each post 10 is slidably mounted a rack bar 60, the toothed face of which registers with a slot 61 cut in the face of the post 10. Between the upper 15 end of this rack bar 60 and a plug 61', screw threaded into the upper end of the post 10 is interposed a coiled expansion spring 62. This spring is maintained at all times under a predetermined pressure in the following 20 manner: Between the lower end of the spring and the head of the rack bar is seated a washer 63 having opposed fingers 64 which extend through relatively short closed slots 65 cut in the side of the tubular post 10. 25 The downward movement of the washer 63 is thus positively limited regardless of the position of the rack bar 60. This spring permits of yieldable engagement between the bottles and the fillers when the bottles 30 are reciprocated upwardly, thus making an air tight fit between the fillers and the mouths of the bottles. It may be here noted that the tension of the spring 62 is such that when the rack bar is moved upwardly the 35 post 10 moves with it as a unit. The lower end of each rack bar terminates short of the closed lower end of the post 10 in order to permit of limited movement of the post independent of the rack bar during the opera- 40 tion of capping.

Describing now the manner of reciprocating the rack bars, the ring like casting 6 is provided at its outer periphery with a series of downwardly extending brackets 66 into 45 each of which is screw threaded a journal stud 67 upon which is rotatably journaled a bearing sleeve 68. The inner end of each of these sleeves is provided with a gear 69 which projects through the slot 61 of the 50 post 10 and meshes with the corresponding rack 60. The outer end of each sleeve is provided with a beveled gear 70 which rides between a pair of circumferentially opposed tracks 71 and 72 respectively. These tracks 55 are respectively secured to the vertical standards 29 by means of brackets 73 and 74. Upon the lower cam track 71 is mounted a relatively short gear rack 75, and upon the opposed upper track 72 is secured a similar 60 rack 76. Upon each gear 70, 70 is mounted a cam roller 78, which is adapted to ride upon the cam surface of the lower track 71 except when the gears engage the respective 65 rack bars 75 and 76. The arrangement is such that as the main frame is rotated, the

cam rollers ride upon the cam track without performing any function until they engage the lower rack 75. Thereupon the gears are rotated through one revolution and the rack bars reciprocated bodily upwardly in the manner described. As the gears leave the rack bar, the rollers again engage the cam surfaces and the gears ride idly along the track. Accordingly, the rack bars and supported bottles are held in their 70 uppermost position, *i.e.*, in operative engagement with the filling apparatus.

After the bottles have been filled, the gears 70 mesh with the upper rack bar 76 and are rotated in the reverse direction. 80 This, of course, causes the rack bars to descend and the bottles pass out of engagement with the filling tubes. The bottles are now ready to be capped. Means must be provided, however, for bringing the filled 85 bottles and the capping devices into alignment with each other. To this end the frame ring-like casting 6 is provided with a series of circumferentially extending bosses 79 within each of which is journaled a bushing 90 79'. Within each of these bushings is slidably mounted a rod 80 the upper end of which extends through the base cap 24, and the lower end of which extends through the bracket 12. To the upper end of this rod 80 95 is secured a bell crank 81 having a pin 82 extending into the slide 25. To the bushing 79' is fixed a similar bell crank 83 having a horizontally extending rod 84. This rod extends through a suitable bore in the stud 100 67 and is provided at its outer end with a roller 85. Each of these rollers 85 rides in a grooved cam track 86 which is secured to the upper main cam track 73. This cam track is so shaped that after the bottles 105 have been filled, the rods 84 and connected bell cranks will be operated and the slides 25 shifted bodily outwardly. In order that the rods 80 may rotate with the bushings 79' they are splined to the latter as shown at 110 87. This latter connection permits of the rods being shifted bodily upwardly with the holders during the filling operation and at the same time permitting the bushings to remain stationary as far as vertical movement is concerned.

After the rests 26 have been brought into alignment with the cappers 52 they are shifted upwardly in order to apply the caps. Within each cylindrical socket member 14, 120 hereinbefore referred to, is reciprocally mounted a sleeve 88, closed at its lower end, and open at its upper end. Within each of these sleeves is seated a plunger 89 closed at its lower end as shown at 90. In order to 125 secure an air tight fit between the plunger and sleeve, the latter is provided with a gland and nut in the ordinary manner. To limit the upward movement of the plunger, the sleeve is provided with an internal 130

shoulder 91. In order to more readily assemble the parts, the sleeve is of two-part construction as shown. The space between the closed lower end of the plunger and the bottom of the sleeve forms an air-tight chamber 92 which communicates with the main air chamber 5 by means of flexible pipes 93. A predetermined pressure is maintained in the main air chamber 5 and the connected chamber 92 by means of a pump 94 and pipe connections 95 controlled by suitable valve mechanisms. Inasmuch as in practice the same size bottles frequently have such inequalities in size that they will break during the operation of capping unless means are provided for permitting them to yield after a predetermined pressure has been applied. The air cushions formed in the chambers 92 above described secure the above result in a simple manner and avoid the necessity of springs or other similar mechanism. This, of course, results from the fact that as the sleeves 88 are shifted upwardly to bring the bottles into operative engagement with the cappers, the plungers ride upon the air cushions and yield sufficiently to compensate for different length bottles. It is to be noted that just previous to the operation of capping, the posts 10 have been lowered into the plungers as shown more clearly in Figs. 3 and 4. Upon the lower end of each sleeve 88 is journaled a cam roller 96 which rides upon a cam track 97 mounted upon the base frame 1. When these rollers ride upon the raised surface 98 of the cam track as shown more clearly in Fig. 3, the bottles are reciprocated upwardly into operative engagement with the cappers. When the rollers have passed over the cam surface, the bottle holders are lowered to their normal position by gravity, and after the operation of capping, the bottles are automatically shunted out of the holders on to a table 99 by means of a deflecting bar 100 in a well known manner.

45 The pump is automatically operated by means of one or more cam blocks 101 which engage the roller 102 and operate the plunger 103 of the pump. The plunger may be restored by any suitable spring mechanism (not shown).

In order to constantly rotate the main frame of the machine, to the ring-like casting 6 is secured a circumferentially extending gear 104 which is adapted to mesh with a pinion 105 carried by stub shaft 107 journaled in a bracket 106 connected to one of the posts 28. The upper end of the stub shaft 107 carries a beveled gear 108 which meshes with a similar gear 109 mounted, 55 upon a main driving shaft 110. The latter is journaled in a suitable bracket 111 secured to the post 29. To this main shaft 110 is secured a pulley 112 which is driven in any suitable manner.

I claim as my invention:

1. In a bottle handling apparatus, the combination with a rotary main frame, of a set of sealing devices rotating in said main frame, a set of bottle holding devices carried by said main frame and normally out of alinement with said set of sealing devices, means for shifting a portion of one set of said devices in alinement with the others, and means for yieldably supporting the bottle holding devices during the operation of capping.

2. In a bottle handling apparatus, the combination with a rotary main frame, of a set of sealing devices rotating therewith, bottle holding devices carried by said main frame and normally out of alinement with said sealing devices, means for shifting members of one set of devices into alinement with the corresponding members of the other set, and an air cushion for yieldably supporting the bottle holders during the operation of capping.

3. In a bottle handling apparatus, the combination with a rotary main frame, of a set of sealing devices rotating therewith, bottle holding devices carried by said main frame and normally out of alinement with said sealing devices, and means for shifting the members of one set of devices into alinement with the corresponding members of the other set of devices.

4. In a bottle handling apparatus, the combination with a plurality of sealing devices, bottle holding devices associated therewith, means for bringing said devices into operative engagement, an air cushion for each of said bottle holding devices for yieldably supporting the latter during the operation of sealing, and a common air chamber having uninterrupted communications with said air cushions.

5. In a bottle capping machine the combination with a plurality of sealing devices, of a plurality of bottle holding devices associated therewith, a plunger for each bottle holding device, an air cushion chamber for each plunger in which the latter is yieldably supported during the operation of sealing, a common air chamber connected to each air cushion chamber and means for bringing the sealing devices and the bottle holders into operative relation.

6. In a bottle capping machine, the combination with a set of bottle holding devices, of a set of sealing devices, cam mechanism for bringing said devices into operative engagement, a plurality of air cushions for cushioning said devices during the operation of sealing and a common air chamber communicating with said air cushions.

7. In a bottle handling machine, the combination with a set of sealing devices, of a set of bottle holding devices associated there-

with, cam actuated mechanism for bringing said devices into operative engagement, of a common air chamber associated with one set of devices for maintaining a substantially uniform pressure during the operation of sealing.

8. In a bottle capping machine, the combination with a rotary main frame, of sealing devices rotating therewith, a hopper comprising a stationary member and a rotating member, a plurality of feeding chutes for conveying the caps from the hopper, to the sealing devices, said chutes being connected to and traveling with the rotating member.

15. 9. In a bottle handling apparatus, the combination with a rotary main frame, of bottle holders carried thereby, sealing devices rotating with said main frame, and bell crank mechanism for shifting the bottle holders into and out of alignment with the sealing devices.

10. 10. In a bottle capping machine, the combination with a rotary main frame, of a stationary main frame, sealing devices supported by said stationary main frame, means for connecting said sealing devices to the rotary frame whereby the sealing device rotates with the latter, a hopper supported by said stationary main frame and comprising

a stationary and a rotary member, means for connecting the rotary member of the hopper to the rotary main frame to rotate with the latter and a plurality of chutes rotating with the rotary frame.

11. In a bottle handling machine, the combination with a rotary main frame, a plurality of bottle holding devices, and a plurality of sealing devices rotating with said main frame, mechanism for bringing said devices into operative relation, a plurality of air cushions for cushioning said devices during the operation of sealing, and a pump for maintaining substantially constant air pressure on said cushions.

12. In a bottle handling machine, the combination with a rotary main frame with a set of sealing devices and a set of bottle holding devices associated therewith, mechanism for bringing said devices into operative relation, a plurality of air cushions for cushioning said devices during the operation of sealing, and an air chamber communicating with said cushions.

HENRY J. CHILTON.
